WORK HOLDING DEVICE

Robert N. Sandberg, Beverly, Mass., assignor to
 United Shoe Machinery Corporation, Paterson, N. J., a corporation of New Jersey

Application November 22, 1933, Serial No. 699,201

2 Claims. (Cl. 164—79)

This invention relates to work-holding devices and is herein illustrated as embodied in a device for holding sheet material such as cloth in operative position upon the cutting bed of a machine for producing shoe part blanks from the material.

In the cutting of shoe part blanks it is common practice to make use of a machine known as a clicking machine of the type illustrated in Letters Patent of the United States No. 921,503, granted May 11, 1909, upon an application filed in the name of A. Bates. This machine comprises a cutting bed and a presser arm swingable laterally over the bed and arranged for movement toward and away from the bed in producing a pressure-applying operation upon a freely movable die, located upon sheet material positioned on the bed, to cut blanks from the material. In connection with the cutting operations performed by such a machine and particularly when it is desired to produce in a single operation a number of blanks from a plurality of layers of sheet material such as cloth, as in producing linings for shoes, it is found desirable to clamp the material to the bed. This is desirable particularly when operating upon the ends of long strips of material, because the weight of the portions of the strips not directly supported by the bed is ordinarily sufficient to pull the ends of the strips off of the bed. Heretofore, various work-holding devices, commonly called cloth clamps, have been devised and have been utilized with varying degrees of success. One difficulty experienced in the use of such device is that, in some instances, parts of the devices project forwardly of the cutting bed in such a way as to interfere with the operator in his movements in locating the dies and in operating the machine. Further than this, considerable difficulty has been experienced in so holding the material, particularly where such material comprises a plurality of layers, that the material will be firmly held during the cutting operation but also in such manner that it can be shifted to a new position to expose fresh surfaces of the material to operation of the machine.

In view of all this, it is an object of the invention to provide a novel work-holding device which will be comparatively simple and economical in construction and effective in its operation. To this end and as illustrated, the invention comprises in combination with a work-supporting bed, a work-engaging apron and an arm movable into juxtaposition to the apron for clamping work pressed between the apron and the arm. Pref-

erably, and as shown, the apron is inclined relatively to the work-supporting surface of the bed and the arm is mounted for movement about an axis parallel to the surface of the bed and has a curved surface adapted to cooperate with the inclined apron to clamp the work. The arm is effective to exert pressure upon one or upon a plurality of layers of material to hold such material in place on the cutting bed but, at the same time, will permit the movement of the material when desired.

Other objects and features of the invention will be apparent from the following detailed description when taken in connection with the accompanying drawings and will be pointed out in the claims.

In the drawings,

Fig. 1 is a perspective view of a portion of a clicking machine embodying one form of the novel work-holding device; and

Figs. 2 and 3 are side and end views, respectively, of the mounting for the apron and arms.

As shown in the drawings, the work-holding device is attached to the bed of a clicking machine which comprises a frame 10 having a cutting block support 12, a cutting block 14 and a presser arm 16 adapted for lateral movement over the block 14 about the axis of its supporting post 18 and arranged for movement toward and away from the block 14 in applying pressure to work such as sheet material 20 positioned upon the block.

As shown, the sheet material 20 may comprise a plurality of layers of cloth suitable for the production of linings for shoes. This material usually comes in long sheets which may be carried in a roll below the bed 12, the ends of the sheets being brought up over the side of the block 14 and located upon the upper surface thereof in position to be operated upon by the presser arm 16. As successive portions of the material have been operated upon to produce blanks, for example, by means of freely movable cutting dies, fresh portions of the material are drawn up over the side of the cutting block and located on the upper surface thereof.

The device as herein shown is adapted to hold the material upon the upper surface of the cutting block. To this end the device comprises an apron 22 and cooperating arms 24 adapted to grip and hold the material 20 along the side of the block 14.

The apron 22 preferably comprises a wooden board having slots 26 in the ends thereof in which are positioned bolts 28 operative to secure the

- apron to brackets 30 which, in turn, are secured to the frame of the machine. The brackets 30, and their associated structure as well as the arms 24 at opposite sides of the machine are similar, and consequently, it will be sufficient to describe the structure shown at the right side only of the machine, (Fig. 1). Each of the brackets 30 is provided with an inclined face 32 against which the apron 22 is positioned so that the apron is held (as shown in Fig. 2) at an inclination of about 15° to the vertical, slopes rearwardly and upwardly toward the forward edge of the cutting block 14, and extends along the forward side thereof. The bracket 30 is provided with a slot 34 through which passes a bolt 36 for securing the bracket to a second bracket 38 having a similar slot 40. The bracket 38 in turn is secured to the bed 12 by bolts 42 extending through an elongated slot 44 in the bracket 38. The slot 44 provides for adjustment of brackets 30 and 38 toward and from the front of the cutting block 14 and the slots 34 and 40 provide for adjustment of the bracket 30 and, consequently, of the apron 22 heightwise of the cutting block 14.
- 25 Each of the arms 24 comprises a rod mounted for movement along a plane which extends at an acute angle to the face of the apron and parallel to the forward edge of the cutting block 14. To this end, each arm has a supporting portion 46 extending at right angles to the body portion of the arm and loosely mounted in spaced ears or bearings 48 upon the bracket 30. To provide for adjustment of the arms 24 axially of the portion 46, that is, toward and from the apron, to accommodate wide variations in the thickness of material located between the arms and the apron, the portion 46 is provided with a flat surface 50 which is engaged by a set screw 52 borne by a collar 54 surrounding the portion 46 and positioned between the ears 48. The width of the collar is less than the distance between the ears so that a limited amount of axial movement of the arm portion 46 is permitted without releasing the set screw 52.
- 45 Each of the arms 24 has at its end a curved projection 56 adapted to engage the upper surface of material located between the arms and the apron 22. The purpose of the curved projections is to provide for the clamping of the material against the apron 22, the arrangement of the curved surfaces of the projections 56 and the inclined face of the apron being such as to make projections contact with the material over a narrow area when the arms are forced downwardly into engagement with the surface of the material. The curved surfaces of the projections make it possible for the arms to accommodate themselves to different thicknesses of material, the position of the areas of contact varying with the thickness of the material.
- 55 In order to hold the arms against the material in engagement with the apron with sufficient pressure to maintain the material in position there is provided mechanism for applying pressure to each of the arms. This mechanism comprises a spring 58 one end of which is secured to a pin 60 on the bracket 30 and the other end of which is secured to a pin 62 carried by an arm 64 mounted upon the end of the rod portion 46. The arm 64 is secured in position on the arm portion 46 by a set screw 66 which engages a flat surface 68 on the portion 46. When the arm 24 at the right of Fig. 1 is rotated into horizontal position such as that shown in Figs. 1 and 2, the

pin 62 will be located inwardly of a line between the pin 60 and the axis of the portion 46 with the result that the force of the spring 58 will act in a direction to rotate the portion 46 counterclockwise (in Fig. 1) to force the arm 24 and its projection 56 in a downward direction in which case the projection 56 will clamp the work against the apron 22. When the arm 24 is moved into inoperative position, that is, to a substantially vertical position, the pin 62 will be located so that the spring 58 extends along a line outside of the axis of the member 46 with the result that the member 46 will be rotated in a clockwise direction (Fig. 3) and the arm 24 will be held in inoperative position. To limit movement of the arm 24 the arm 64 is provided with lugs 70 and 72 which are adapted to engage, respectively, opposite surfaces 74 and 76 of a lug 78 on the bracket 30.

20 In the operation of the device the end of the work such as a plurality of layers of cloth is placed upon the upper surface of the cutting block 14 and the arms 24 are rotated from their inoperative substantially vertical positions to substantially horizontal positions illustrated in Fig. 25 1, the springs 58 forcing the arms 24 downwardly with the result that the curved surfaces of the projections 56 will cooperate with the inclined face of the apron 22 to clamp the material in position. When it is desired to place a fresh surface of the work upon the block 14 the material is pulled back over the block which is possible because of the fact that friction between the surface of the material and the surfaces of the projections 56 will tend to move the arms 24 upwardly to release the pressure exerted by them. The springs 58 will cause the projections 56 again to grip the material in its new position. When new material is to be positioned upon the cutting block the arms 24 can be rotated upwardly and outwardly, and will be held in inoperative position by the springs 58.

30 Thus it will be seen that the invention provides a comparatively simple device for effectively holding work in position upon its supporting bed 45 or cutting block and at the same time has eliminated any necessity for mechanism which will interfere with the operator in his carrying out operations upon the material.

Having described my invention, what I claim 50 as new and desire to secure by Letters Patent of the United States is:

1. A work-holding device comprising a work support, an apron adjacent to an edge of the support and having a work-engaging face extending at an inclination to the surface of the support, and a pair of arms pivotally mounted upon the support for movement substantially in a plane extending longitudinally of the face of the apron and at an acute angle thereto from inoperative positions to positions in which the arms engage the surface of work extending over the face of the apron.

2. A work-holding device comprising a frame, a work-support carried by the frame and having a work-engaging face, an arm pivotally mounted upon the frame and having a free end portion arranged for movement along and toward said work-engaging face substantially in a plane oblique thereto into position to wedge between the end portion of the arm and the support work located upon the support.
